(57) **CLAIM**

The ornamental design for a self-driving truck, as shown and described.

DESCRIPTION

The file of this patent contains at least one drawing/photograph executed in color. Copies of this patent with color drawing(s)/photograph(s) will be provided by the Office upon request and payment of the necessary fee. The portion of the design shown in the color "Yellow" is for the purpose of illustrating a portion of the article that forms no part of the claimed design.

1. Self-driving truck
- 1.1 : Front
- 1.2 : Back
- 1.3 : Left
- 1.4 : Right
- 1.5 : Top
- 1.6 : Perspective
- 1.7 : Perspective

Reproduction 1.1 is a front view of a self-driving truck, showing our new design; reproduction 1.2 is a back view thereof; reproduction 1.3 is a left view thereof; reproduction 1.4 is a right view thereof; reproduction 1.5 is a top view thereof; reproduction 1.6 is a front perspective view thereof, and reproduction 1.7 is a back perspective view thereof.

1 Claim, 7 Drawing Sheets
